CLAIM

The ornamental design for a cradle for a communications headset, as shown and described.

DESCRIPTION

FIG. 1 is an upper front left perspective view of a base cradle for a communications headset, the base cradle having a cradle and a base, the broken line drawing of the base of the base cradle in the drawings herein is for illustrative purposes only and forms no part of the claimed design.

FIG. 2 is a front elevational view of the base cradle.

FIG. 3 is a right side elevational view of the base cradle.

FIG. 4 is a left side elevational view of the base cradle.

FIG. 5 is a rear elevational view of the base cradle; and,

FIG. 6 is a top plan view of the base cradle.
